UNITED STATES PATENT OFFICE.

EUGENE L. BAKER, OF TAUNTON, MASSACHUSETTS.

RANGE.

1,379,954.

Specification of Letters Patent.

Patented May 31, 1921.

Application filed October 30, 1920. Serial No. 420,845.

To all whom it may concern:

Be it known that I, EUGENE L. BAKER, a citizen of the United States, residing at Taunton, in the county of Bristol and State 5 of Massachusetts, have invented a new and useful Range, of which the following is a specification.

This invention relates to cook stoves or ranges of the combined coal and gas type.

10 Heretofore it has been the practice to provide a finishing flange or apron of nickel or the like along the front portion of the top of the coal burning section of the range and to terminate this flange or apron in 15 front of the gas burning portion in order to allow proper positioning of the gas cocks which have been extended upwardly from the gas manifold. As a result the appearance of the complete range has been marred 20 and the proper protection against accidental turning of the cocks has not been afforded.

One of the objects of the present invention is to provide a range in which the front flange or apron is extended continuously 25 along the top of both the coal burning section and the gas burning section of the range, thereby not only increasing the attractiveness of the range but also providing a guard to prevent accidental turning of the gas 30 cocks.

With the foregoing and other objects in view, which will appear as the description proceeds, the invention resides in the combination and arrangement of parts and in 35 the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a front elevation of a portion 45 of a combination range having the present improvements.

Fig. 2 is an enlarged front elevation of a portion of the flange or apron and showing more clearly the position of the gas manifold and cocks relative thereto.

Fig. 3 is a section on line 3—3, Fig. 2.

Referring to the figures by characters of reference A designates a portion of the coal burning section of a combination range and

B designates a portion of the gas burning section of the range. Extending along the front of the top of both portions of the range is a continuous curved apron or flange 1 and supported back of this flange or apron at the front of the gas burning portion B is 60 a gas manifold 2 from which are extended gas cocks 3 arranged between the manifold and the inlet stems 4 of the burners 5. The handles 6 of the gas cocks are arranged below the manifold and back out of the way 65 where they can only be reached by placing the hand under and back of the apron or flange 1 as will be apparent by referring to Fig. 3.

Obviously by arranging the parts as herein 70 described the stove presents a much more attractive appearance than where the flange or apron 1 is not extended in front of the gas burning portion B. Importance is also attached to the fact that by arranging the 75 gas cocks in inverted position as shown it is possible to set the manifold up back of the flange or apron 1 where it is partly concealed, thereby supporting the handles of the gas cocks at points where the chances of 80 turning them accidentally are materially lessened.

While the improvements have been shown and described in connection with a combination range it is to be understood that they 85 can also be used on gas ranges without the coal burning sections.

What is claimed is:—

1. In a combination coal and gas range the combination with a gas manifold, gas 90 burners, and gas cocks interposed between the manifold and burners and having their handles underneath, of a continuous finishing flange extending outwardly and downwardly from the range and extending continuously along the front of the coal burning and gas burning portions and partly housing the manifold.

2. A combination coal and gas burning range having a gas manifold, gas burners, 100 gas cocks interposed between the manifold and burners with their handles below the manifold, and a flange extending continuously across the front of the coal and gas burning portions and partly housing the 105 manifold.

3. In a range the combination with a gas manifold, gas burners, and gas cocks inter-

posed between the manifold and burners and having their barrels vertical and the handles underneath, of a continuous finishing flange extending outwardly and downwardly from the range and extending continuously along the top of the range and partly housing the manifold.

In testimony that I claim the foregoing as my own, I have hereto affixed my signature in the presence of two witnesses.

EUGENE L. BAKER.
